AIR MOTOR

Cleo Harris and Clyde G. Butler, Cincinnati,
Ohio, assignors to The Cincinnati Ball Crank
Company, Cincinnati, Ohio, a corporation of
Ohio

Original application July 27, 1931, Serial No.
553,297, now Patent No. 1,981,507. Divided and
this application August 25, 1933, Serial No.
686,793

5 Claims. (Cl. 121—164)

This invention relates to air motors and is particularly directed to an air motor of the type incorporating an automatically actuated reversing valve for constant reciprocation of a piston. 5 This application is divisional of application Serial Number 553,297 filed July 27, 1931 by Cleo Harris and Clyde G. Butler now Patent Number 1,981,507 issued July 20, 1934. As disclosed in the original case, the air motor is applied to the pumping piston of the grease pump.

The mechanism for operating or changing the position of the air inlet and exhaust valve is controlled by the movement of the piston so that after a predetermined stroke of the piston in either direction the valve is tripped and the air supply and exhaust connections are alternately made to the cylinder for continuous reciprocation. 15

20 It is an object of this invention to provide an improved air motor of the continuously operating type in which a reversing valve is included, which valve is actuated by the piston at predetermined positions of its movement and is operated by an improved automatically tripped mechanism, whereby by the air motor cannot stall and the reversal of the piston occurs positively and accurately for uniformity and regularity of stroke.

25 It is a further object to improve the structure 30 of the valve exhaust seat, whereby the constant engagement of the valve with the seat does not unduly wear the seat, and at the same time the seat is of a yieldable material for insuring a positive seal.

35 It is a further object of this invention to provide an improved arrangement of the air inlet relative to the control valve, whereby the valve is held against the particular seat through the medium of the air, this applying to both the 40 inlet and outlet valves. This is a valuable improvement in that the air serves as an auxiliary means for holding the valve in closed position even when the valve operating mechanism may 45 be effective for this purpose.

45 It is a further object of this invention to provide a valve operating mechanism which imparts a snap action to the valve for a minimum amount of time and a positive seal in the transfer of the valve from one seat to the other so that the 50 reversal of the air flow is accomplished substantially incidentally with the time the piston has moved the prescribed amount.

55 Other objects and further advantages will be more fully apparent from a description of the accompanying drawings, in which:

Figure 1 is a general view of a portable transfer pump incorporating the improved air motor, showing the pump mounted relative to an 60 original container, the original container being

broken-away for more fully illustrating the pump.

Figure 2 is a sectional view taken on line 2—2, Figure 1, generally detailing the air motor and the grease pump operated thereby.

5 Figure 3 is an enlarged sectional view taken on line 3—3, Figure 2, illustrating the air motor in detail, showing the valve in position for permitting air supply to the piston thereof for a power stroke.

Figure 4 is a sectional view taken on line 4—4, 10 Figure 3, further detailing the air motor.

Figure 5 is an enlarged diagrammatic view showing the relation of the valve, valve seats, and stem for the purpose of accomplishing an 15 unbalanced condition.

The air motor construction of this invention, as stated, has been illustrated in conjunction with the portable grease pump of the character disclosed in the original application.

20 The portable grease pump is of slender character so as to be conveniently and easily inserted into the standard commercial grease container through the average opening and for this purpose includes a generally coaxial arrangement of the major parts. A pumping cylinder 20 is 25 secured on the lower end of a long discharge tube 21, fixed at its upper end to the casing 22 of an air motor unit 23, which air motor casing houses the air control mechanisms for the motor. A pumping piston 24 is located at the lower 30 end of the discharge tube operating within the pump cylinder and is in operative contact with the piston 25 of the air motor through the discharge tube, by means of a piston rod 26.

35 This pump unit is depended into the original container 27 through the opening 28 thereof and is adjustably sustained by means of a closure and support device 29. The container 27 illustrated is of the conventional drum type. The closure and support device 29 includes a circular closure plate 30 having a circular depending flange 31 and adapted to fit over the top of the container with the flange 31 fitting over the edge thereof. This plate has a central aperture 32 40 extended upwardly by means of a split sleeve 33 45 designed to encircle the tube and to be slidable thereon.

50 The split portion of the sleeve is traversed by a draw bolt 34 which may be tightened to set the closure and support device 29 in place when the tube has been adjusted to the depth of the particular tank or container for entirely or substantially emptying the container of grease.

55 The grease drum or container opening is thus entirely closed to prevent the entrance of dirt into the grease. The closure plate 30 is secured in place by means of a plurality of hook bolts 35 depending through openings 36 and adapted to be hooked under the depending flange 37 about 60

the opening of the container and tightened by means of wing nuts 38 screwed into their upper ends. The openings through which the hook bolts extend may be in the form of radial slots 5 or may be large enough to permit some shifting of the hook bolts by utilizing washers 38a under the ring nuts as shown.

The air motor for actuating the pumping piston is effective for producing pumping or forcing 10 strokes under air pressure and a spring means is effective for return of the piston.

In this instance it is arranged that the pumping strokes of the piston moves the grease upwardly through a hollow or tubular lower end 39 of the 15 piston rod 26. The pumping piston 24 is assembled on the lower end of the piston rod by means of a headed sleeve 40 screwed into the bore of the piston rod at the lower end thereof and securing oppositely turned gaskets 41 of the piston against 20 the lower end of the piston rod, these gaskets being spaced by means of a washer 42.

The headed sleeve includes an upwardly disposed valve seat 43 and has a ball valve 44 engaged against the seat, as formed by a converging 25 bore wall at the lower end of the sleeve 40. The ball is preferably held against the seat by means of a coil spring 45 under compression between the ball and the upper end of the bore of the piston rod. As will be apparent the spring compresses 30 and the valve opens to downward stroke of the pumping piston. The grease passes through the tubular lower end of the piston rod and is discharged upwardly and outwardly through a port or ports 46 extending from the interior of the 35 hollow piston rod into the tube 21 above the pumping cylinder for discharge upwardly through the tube.

The piston rod 26 is slidably mounted at its lower end within the central bore of a tube closure 40 cap or coupling 47 which is threaded into the lower end of the tube and provides the bored intermediate wall for guiding the piston rod. This element 47 also functions as a coupling device whereby the pumping cylinder 20 is screwed 45 thereon. This closure cap or coupling means also serves for maintaining the piston return spring 48 in position of compression within the tube. The piston return spring 48 is maintained under adjustable compression downwardly 50 against the closure cap by means of a nut 49 screwed onto the piston rod and an inverted thimble 50 is inserted at the lower end of the tube, the thimble fitting snugly within the tube and resting upon the shoulder provided by the inserted upper 55 end of the assembly sleeve, the fitting at this point being by means of a counterturned portion 51 on the thimble fitting over the inserted end of the sleeve. A cotter pin 52 maintains the nut 49 in set position.

60 A gasket 54 is held between the coupling element or cap 47 and the thimble and is engaged about the piston rod at the point where it traverses the coupling element or cap 47 for sealing the sliding rod at this point. Since the thimble 65 50 surrounds the piston rod at the point of grease discharge outlet 46 of the hollow rod, the thimble includes outlet ports 53 in its upper end for permitting flow of grease directly into the tube.

For the purpose of preventing the vacuum 70 which would occur at the top of the piston 24 within the pumping cylinder 20, a series of radially disposed apertures 55 are provided through the pump cylinder wall permitting the grease to enter above the piston.

75 By the arrangement of parts described at the

base of the gun, it will be apparent that the assembly of the pump at this point is extremely efficient.

With the piston rod in place within the tube, the piston return spring 48 is inserted against the nut 49 and the thimble 50 and gasket are placed upon the coupling sleeve or closure cap 47, the coupling sleeve or cap 47 thereupon being screwed into the lower end of the tube thereby compressing the return spring into position whereupon it is 10 conveniently possible to attach the parts of the piston 24 to the rod 26 and to screw the pumping cylinder 20 into position about the pump piston.

An inlet valve 19 is provided for the pumping cylinder at its extreme lower end which valve is 15 adapted to open on upstroke or intake stroke of the piston and to close on downstroke or discharge stroke.

The piston rod at its upper end is slidably mounted in the lower end of the air motor casing 20 22. The air motor casing is in three parts, including, an air motor cylinder section 56, a lower cylinder head section 57, which slidably mounts the piston rod 26 and into which the tube 21 is screwed, and the upper cylinder head section 58 25 including a casing which houses the air motor control valves and operating mechanism. The lower head 57 has a discharge passageway 59 disposed radially from the bore 60, into which the tube 21 is screwed. A meter 61 for measuring 30 the discharge of the pump is screwed into this passageway and a flexible hose 62 extends from the meter. The hose is of sufficient length for carrying the discharge to the point of service. A suitable valve mechanism and manual control 63 is included at the outer end of the discharge hose for controlled delivery of the grease. The valve and control are not illustrated in detail herein since this apparatus forms the subject matter of a separate invention.

40 The piston rod 26 is sectional including two sections which are pivotally joined. The lower end of the upper section 64 is bifurcated and the end of the lower section 65 extends into the bifurcations and is pivotally secured in place 45 therein by means of a cross pin 66. A packing gland 67 is screwed into the head 57 for sealing the sliding rod within the head.

The piston rod is made sectional for receiving the nut 49 on a screw-threaded portion thereof, 50 the lower section being counterturned over its major portion with the exception of its lower slidably mounted end. The piston section 64 and the lower end of the section 65 are of the same 55 diameter whereby the pressure imparted to the upper section 64 through contact with the piston 25 of the air motor is effective over the same area in the lower end of the section 65. It will be observed that this would not be true if the counterturned upper end of the lower section were in contact with the air motor piston.

The piston rod assembly 26 extends into the air motor cylinder and the air motor piston 25 engages against its upper end. The air motor piston includes a pair of discs 68 screwed together upon a gasket 69 which engages the walls of the cylinder and is disposed upwardly for action of the air thereagainst from above. The elements of the piston are clamped upon the head 70 of the piston rod 70 for the air motor piston which extends upwardly through the upper disc and is slidably mounted through the upper cylinder head 58. A packing gland 71 is provided 75 at the point where the piston rod 70 traverses the

cylinder head 58 for sealing the cylinder at this point.

The air is supplied to the air motor 23 through a pipe 72 extending from the main supply conduit 73, this pipe 72 connecting to the upper end of the air motor casing. A valve 74 is mounted in the passageway 75 to which the pipe 72 connects. This passageway 75 extends from the valve downwardly through the upper cylinder head and enters the air motor cylinder above the piston. The opening and closing of the valve is automatically controlled by the movement of the air motor piston through its piston rod 70 which actuates a toggle mechanism, the toggle mechanism acting upon the stem 76 of the valve 74 which stem is slidably mounted within the casing in the position parallel to the piston rod 70.

The valve stem 76 has a screw-threaded counterclockwise upper end upon which is screwed the valve element. The valve element 74 is held against the shoulder formed by the counterclockwise by means of a sleeve nut 77 screwed onto the threaded portion from above. Two valve seat elements are provided, one 78 above and the other 79 below the valve element, the lower one functioning to cut off the air supply during the exhaust stroke of the air motor and the upper one functioning to cut off the exhaust when the supply is taking place.

30 The lower valve seat 79 is disposed within the lower end of a bore in the casing which houses the valve assembly and includes suitable packing 80 engaged about the valve stem.

The bore within the lower valve seat element 35 through which the valve stem passes, provides ample clearance for the passage of air, the air entering this bore through radial apertures 82 and a circumferential groove 83 which is supplied from the radially extended air supply passage 75.

The upper valve seat element is spaced from the lower valve seat element by means of a spacer sleeve 84 encircling the valve element 74 and providing ample clearance for movement of the 45 valve thereof and air passage. The upper valve seat element includes a flange 85 resting upon the upper end of the casing about the bore and a central bore clearing the valve assembly to permit air exhaust upwardly from the valve chamber.

50 The valve seats 78, 79 and the spacer sleeve 84 are held in position of assembly by means of an acorn nut 87 screwed onto the casing and upon the flange 85 of the upper valve seat. This nut includes a series of radially disposed exhaust ports 88. Packing 89 is provided under the respective heads of the valve seat elements where they abut the casing. The valve is adapted to move between the opposing and spaced seats thus provided, the seats proper being provided in both 60 instances by circular bosses or raised portions on the respective elements.

In the instance of the upper valve seat to prevent undue wear of the seat and to provide a positive seal when the air is being supplied to the air motor, the seat combines metal and leather, rubber or some yieldable composition. For this reason a circular or annular lip 90 is extended from the valve seat element and a washer 91 equal in thickness to the height of the lip is disposed around the same and engaged against the under side of the valve seat element. Thus, when the valve 74 engages this seat, the contact with the metal and the leather is simultaneous. Great durability and a positive seal for the valve 75 are thus provided.

The intermediate or spacer sleeve 84 is radially ported as at 92 and is grooved medially exteriorly as at 93 to provide passage for the air which passage communicates with the main air passageway 75 to the air motor cylinder. 5 The movement of the air motor piston rod 70 is effective for actuating the valve controlling toggle mechanism and for this purpose is counterclockwise intermediate its length to provide opposing shoulders 94, 94, which shoulders are 10 adapted to alternately engage the toggle.

The toggle elements are engaged to provide a knuckle adjacent the piston rod 70. The respective links 95, 96 of the toggle are pivotally mounted at their outer ends, one of the pivotal 15 mountings being floating and yieldable to permit forced movement of the toggle past dead center and under spring pressure to provide pressure for snapping of the toggle past dead center. The toggle link 95 which has a fixed pivot 95 is of 20 U-shape, straddling the valve stem, and has the rounded ends 97 of its arms engaged in semi-circular grooves formed in offset portions disposed intermediate of the length of the other toggle link 96.

The other toggle link comprises arms respectively disposed at opposite sides of the piston rod 70. The rounded inner ends 98 of the arms of the link 96 are disposed between the arms of the first mentioned toggle link 95 and the outer 30 ends are pivotally mounted on a pivot pin 99 disposed within the swinging end of a pivot bracket link 100 which is pivoted at its lower end in the casing on a pin 100. The swinging bracket 100 includes a pair of side arms and a 35 cross plate 101. The cross plate portion is engaged by one end of a coil spring 102 under compression extending outwardly through a hollow boss 103 of the casing and maintained in position of compression by means of a plug 104 40 screwed onto the casing.

Under the action of the compression spring 102, the links 95, 96 of the toggle are maintained either in upper or lower position, past dead center, with the rounded swinging ends 98 of the 45 toggle links 96 actively engaged against either an upper shoulder 105 or a lower shoulder 106 of the valve stem formed by a counterclockwise portion in the same.

The toggle is designed to act rapidly under the 50 action of the spring. When the air motor piston is at its upper position as shown in Figure 4, the lower shoulder 94 of the piston rod 70 is engaging the toggle links, having forced the same past dead center toward that side, and the swinging ends 98 of the toggle links 96 having engaged the upper shoulder 105 on the valve stem thereby moving the valve into seated position on its upper seat to permit supply of air above the piston and a power stroke thereof.

As the power stroke takes place, the piston moves downwardly under the action of the compressed air moving a distance which is governed by the distance between the shoulders 94, 94 of the piston rod until the upper shoulder 94 of the 65 piston rod engages the toggle at the knuckle thereof. The power piston continuing downwardly forces the toggle by contact therewith at the point of the knuckle downwardly to dead center compressing the spring 102 and storing up 70 energy therein for a quick valve actuation. The moment the toggle passes dead center, the spring 102 under compression rapidly forces the toggle to the opposite side. This swings the swinging ends 98 of the link parts 96 against the lower 75

shoulder 106 of the valve stem and delivers a quick blow thereto which rapidly moves the valve to the lower seat thereby cutting off the air supply and permitting exhaust through the supply 5 passageway from above the piston as the return spring 48 acts from below.

It will be observed that the opening and closing of the valve on either side is accomplished rapidly insuring positive uniform strokes of the 10 piston. There is no opportunity for the valve to pause between the seats, movement taking place so rapidly that the pump cannot be stopped with the valve at rest intermediate its seats. The toggle acts to deliver a quick blow to the valve 15 plunger, this blow being delivered under the accumulation of force in the spring 102, it being apparent that the valve is not pushed open but is snapped open.

It is provided that the air under pressure is 20 effective for holding the valve in its respective seat positions, particularly while the toggle is travelling between the shoulders 105 and 106, and until the time when the toggle has snapped past dead center and actuated the valve. After 25 this occurrence the valve is held in seated position under the action of the toggle spring, and the auxiliary force of the air under pressure would be unnecessary although it still continues to be effective. This result is brought about by 30 providing an unbalanced condition at the valve. The relative diameters of the valve, stem, and passageway are important and are carefully determined for this purpose. Referring to Figure 5, it will be noted that the valve diameter indicated 35 at A is greater than the largest diameter B of the valve stem within the air inlet chamber insuring positive seating of the valve against the exhaust seat. In the exhaust position the valve is held against the inlet seat because of the 40 fact that the diameter of the passageway indicated at C between the air inlet chamber and the valve chamber is less than the largest diameter B of the valve stem within the air inlet chamber.

45 The lower region of the air motor cylinder below the piston 25 is open to the atmosphere through a pipe 107 screwed into the lower end of the cylinder through the cylinder head and depending into the tank through an opening 108 50 in the closure means. This prevents formation of a vacuum in the cylinder and permits the return to the tank of any grease escaping into the cylinder from the grease discharge tube.

Having described our invention, we claim:

55 1. An air motor, comprising, a piston and cylinder, an air supply conduit means connected to the cylinder of said air motor, a valve in said conduit means, said valve including a stem, said air motor piston including a rod, and a valve 60 control toggle having its knuckle directly engaged by said piston rod, one of the arms of said toggle extended beyond the knuckle and acting on said valve stem for alternate admission of air into the motor cylinder and exhaust 65 therefor, said valve stem and piston rod disposed between the pivots of said toggle, said valve control toggle arranged for delivering snap action to the valve stem at the limits of stroke of the piston for rapid opening and closing 70 thereof.

2. An air motor, comprising, a piston and cylinder, an air supply conduit means connected to the cylinder of said air motor, a valve in said conduit means, said valve including a stem, said air motor piston including a rod, a valve control

toggle mechanism having its knuckle directly engaged by said piston rod for movement past dead center, said toggle having one of its arms extended beyond the knuckle and in position at each side of dead center engaging said valve 5 stem for opening and closing said valve for alternate admission of air into the cylinder and exhaust therefrom, and a spring for urging said toggle into said positions at each side of dead center whereby the toggle mechanism is effective 10 for delivering quick action to the valve at the limits of stroke of the piston.

3. An air motor, comprising, a piston and cylinder, an air supply conduit means connected to the cylinder of said air motor, opposing valve 15 seats in said supply conduit means, a valve in said supply conduit means movable between said opposing seats for alternate supply and exhaust of the air to and from the cylinder, said valve including a stem having opposing shoulders; said air motor piston including a rod having opposing shoulders, a valve control toggle having its 20 knuckle disposed for alternate engagement by the shoulders of said piston rod, said valve stem and piston rod disposed between the pivots of 25 the toggle, a spring for normally maintaining said toggle in either of said positions of alternate engagement, and said toggle having one of its arms extended beyond the knuckle and adapted to alternately engage the opposing shoulders of 30 said valve stem whereby as the toggle is moved through dead center by piston rod movement, the spring acts to deliver a snap action to the toggle for reversing the position of the valve on its seats at the limits of stroke of the air motor 35 piston.

4. An air motor, including a cylinder and a piston, an air supply passageway for said cylinder, opposing inlet and exhaust control seats in said passageway, a valve operative between 40 said seats, said valve including a stem, said piston including a piston rod disposed parallel to said stem, said stem and piston rod respectively having opposing shoulders formed thereon, a toggle having its knuckle disposed in the path 45 of movement of said piston rod shoulders and having an inner arm end alternately engageable with the shoulders of said valve stem, a swinging pivot for one of the toggle arms, a spring for imparting pressure against the swinging pivot 50 to normally maintain the toggle arms out of alignment whereby alternate engagement of the knuckle by the respective shoulders and piston rod moves the toggle past dead center and causes the spring to impart a snap action alternately 55 moving the said inner arm end against the shoulders of the valve stem for actuation of the valve.

5. An air motor including a piston and a cylinder, comprising, a valve casing providing a chamber, a conduit extending from said valve 60 chamber to said cylinder, an exhaust conduit extending from said valve chamber, a supply conduit extending to said valve chamber, a valve in said chamber including a stem, valve seats between the inlet conduit and the valve chamber and between the valve chamber and the exhaust conduit respectively, said valve stem slidably mounted through the inlet conduit and said valve having a diameter greater than the largest diameter of the stem within the inlet conduit, and the largest diameter of the stem being greater than the diameter of the passageway 65 from the inlet conduit to the valve chamber.

CLEO HARRIS.

CLYDE G. BUTLER.
